MAGNETIC TAPE MEMORY UNIT ATTACHMENT FOR DIALING A TELEPHONE

Ladd M. Adams, Norman, Okla., assignor to Avo Corporation, Norman, Okla., a corporation of Oklahoma

Filed May 18, 1964, Ser. No. 80,038

Term of patent 7 years

(Cl. D26—14)

FIG. 1 is a front, top and right side perspective view of a magnetic tape memory unit attachment for dialing a telephone, showing my new design;

FIG. 2 is a top plan view;

FIG. 3 is a right side elevational view;

FIG. 4 is a front elevational view;

FIG. 5 is a rear elevational view;

FIG. 6 is a left side elevational view; and

FIG. 7 is a bottom plan view thereof.

I claim:

The ornamental design for a magnetic tape memory unit attachment for dialing a telephone, substantially as shown and described.
